Primary Examiner — Celia A Murphy*Assistant Examiner* — John Windmuller(74) *Attorney, Agent, or Firm* — Kile Park Goekjian Reed & McManus PLLC**CLAIM**

I claim, the ornamental design for a track clip, as shown and described.

DESCRIPTION

FIG. 1 is a perspective view of a track clip, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a cross-sectional view taken along the line '8—8' in FIG. 2.

The broken crosshatch lines in FIG. 8 form no part of the claimed design.
